UNITED STATES PATENT OFFICE.

THOMAS H. FENN, OF CLEVELAND, OHIO, ASSIGNOR OF ONE-HALF TO THOMAS FOULKES, OF CLEVELAND, OHIO.

ELECTRIC-CONDUCTOR COUPLING.

Application filed May 17, 1921. Serial No. 470,377.

To all whom it may concern:

Be it known that I, THOMAS H. FENN, a citizen of the United States, residing at Cleveland, in the county of Cuyahoga and 5 State of Ohio, have invented certain new and useful Improvements in Electric-Conductor Couplings, of which the following is a specification.

My invention relates to improvements in 10 electric conductor couplings, the present embodiment of the invention relating more particularly to that class or type which are adapted to simultaneously connect a plurality of electric conductors through the medium of a plurality of contact elements, the improved device being particularly designed and adapted for use in the walls of factory buildings, machine shops, and the like, in connecting the relatively heavy conductors 20 leading to the various electrically driven machines.

In view of the fact that the connections are made simultaneously with the insertion of the head or plug member into the socket 25 or receptacle the device forms what may be termed a plug-in switch.

The primary object of the invention is to provide a generally improved device for the class indicated which will be exceedingly 30 simple in construction, cheap of manufacture, and efficient in use.

A further and very important object of the invention is to provide a wall socket or receptacle which may be closed when not in use to protect the internal contact elements, or if desired, the cover may be locked to 35 prevent the unauthorized use of same.

With the above mentioned and other ends in view, the invention consists in the novel 40 construction, arrangement, and combination of parts hereinafter described, illustrated in one of its embodiments in the accompanying drawings, and particularly pointed out in the appended claims.

Referring to the drawings forming a part 45 of this specification, Figure 1, is a side elevation of the improved coupling or connector, the parts being in assembled or connected position.

Fig. 2, a top plan view of the same.

Fig. 3, a face view of the same.

Fig. 4, a central vertical longitudinal sectional view of the same taken on line 4—4 of Fig. 2.

Fig. 5, a view of the open or face side of

the wall receptacle or socket when the plug or head member is removed.

Fig. 6, a side elevation of the same with the protecting cover or closure attached.

Fig. 7, a face view of the same with the 60 protecting cover attached.

Fig. 8, a fragmentary side elevation, partly in section, illustrating a modified form of locking device for securing the head and socket members in assembled position. 65

Similar numerals of reference designate like parts throughout all the figures of the drawings.

The improved coupling comprises a socket or wall receptacle 1, and a plug or head 70 member 2. The socket or wall receptacle 1, is preferably of cylindrical form in cross section and particularly with respect to the opening adapted to receive the head or plug member 2, the latter being preferably 75 of cylindrical form in cross section to slidably fit within the opening of the socket.

The socket or receptacle 1, is preferably provided with an insulating member or base 1^a, adapted to carry the contact elements 80 3, connected to the wall terminals or conductors 3^a, the latter, in the present instance, extending out through the side wall of the receptacle or socket provided with an insulating ring 3^b, removably secured by means 85 of a nut 3^c. The insulating base 1^a, may be secured by means of fastening elements 1^b, and the contact elements 3, may be secured by means of fastening screws 3^e, the terminals 3^a, being secured by means of binding 90 screws 3^d.

The plug or head member is made up, in the present instance, of a plurality of disk members, one of said members 2^a, being provided with a plurality of spaced openings 95 2^b, and the other disk member 2^c, being provided with suitable openings 2^d, to slidably receive and contain the spring resisted movable contact elements 4. The contact elements 4, project inwardly from the insulating disk member 2^c, and are correspondingly spaced with complementary contact elements 3, of the socket or receptacle 1. As a means of causing the movable contact elements 4, to be normally projected in front of the face 100 of the plug member and, when the latter is connected, to firmly press against the contact elements 3, coiled springs 4^a, are mounted on the reduced stem portions of the pins and are arranged within the openings 2^b, of the 110

insulating disk 2^a, the terminals or conductors 4^b, being suitably attached to the rear ends of the contact elements 4, and extending through suitable insulating sleeves 2^c, 5 in the plug or head 2.

As a means of joining and locking the socket and plug members in proper position, and particularly as a means of initially engaging the plug member when being inserted 10 whereby such plug member must be brought with its contact elements 4, in circumferential alignment with the contact elements of the socket, said socket and plug members are provided with longitudinally extending 15 guide members 5, and 6, eccentrically located and extending longitudinally of and parallel with the axes of said socket and plug member. In the present instance, the said guide members 5, and 6, comprise tubular members, 20 the tubular guide member 5, preferably extending outwardly slightly in front of the mouth of the socket or receptacle 1, so as to initially engage and slide within the tubular member 6, extending through the plug or 25 head member 2.

As a means of automatically locking the socket and plug members in assembled connected position with the contact elements 3, and 4, in engagement, the tubular guide 6, 30 is provided with a sleeve 6^a, provided at its lower portion with a cable holding sleeve extension 6^b, to receive and carry the main cable 7.

The sleeve 6^a, is secured to the tubular member 6, in any suitable and convenient manner and is provided with a suitable locking device, as for example,—a spring resisted latch member 8, pivotally mounted between bearing lugs 6^b, and provided with an inclined nose or hook 8^a, adapted to snap into a notch or recess 6^c, in the guide member 6. The hook or head portion of the latch is preferably resisted by means of a spring 9, mounted on the sleeve 6^a, by means of attaching screws 9^a.

If desired a locking device in the form of a screw 10, provided with a head having wings 10^a, may be provided as shown in Fig. 8, of the drawings, and in which instance, 50 the screw is mounted in a threaded opening in the sleeve 6^a, and may engage in a notch or recess 6^c, in the guide sleeve or tube 5.

As a means of closing the socket or receptacle 1, when the plug or head 2, is removed, 55 thereby protecting the contact elements 3, and preventing any unauthorized use, the face or mouth of the socket may be closed by means of a cover or closure 11, having an opening to receive the guide 5 (see Fig. 7) 60 and provided with a flanged portion 11^b, which fits down over the marginal edges of the socket, and as a means of securing the cover 11, in position, the latter may be provided with a latch member 12, pivoted on a 65 screw 12^a, and provided with a handle 12^b,

the free end of the latch being adapted to engage in a notch 6^c, in the guide sleeve 5, as shown most clearly in Fig. 7, of the drawings. If desired the cover 11, may be locked thereon by means of any suitable and convenient lock.

Having thus described some of the embodiments of my invention, without having attempted to set forth all the forms in which it may be made, or all the modes of its use, 75 what I claim and desire to secure by Letters Patent, is,—

1. In an electric coupling for simultaneously connecting a plurality of electric terminals and contact elements, cylindrical shaped socket and head members carrying a plurality of electric terminals and relatively fixed and movable contact elements, and longitudinally extending eccentrically located guide members adapted to initially engage and slide over each other whereby 80 said plug member must be brought with its contact elements in alignment with the contact elements of said socket member when inserted.

2. In an electric conductor coupling, the combination with head and socket members provided with relatively movable and fixed contact elements; of eccentrically located longitudinally extending guide members 95 carried by said head and socket members adapted to initially telescope with each other whereby said head member must be moved to a predetermined position circumferentially relative to said socket member thereby bringing said contact elements into alignment with each other when said plug member is inserted.

3. In an electric coupling for simultaneously connecting a plurality of electric terminals and contact elements, cylindrical shaped socket and head members each carrying a plurality of electric terminals and relatively fixed and movable insulated contact elements, respectively, longitudinally extending eccentrically located tubular guide members adapted to engage and slide over each other whereby said plug member must be brought with its contact elements in alignment with the contact elements of said socket member when inserted, said tubular guide of said head members being provided with a cable carrying sleeve and a locking device for securing said guide members in relatively locked position.

4. In an electric conductor coupling, a relatively fixed wall receptacle of cylindrical form in cross section provided in its base with insulated contact elements, a plug member of similar form in cross section 125 adapted to enter said socket receptacle and provided with spring resisted contact elements adapted to register with and make contact with said first mentioned contact elements, a guide member eccentrically lo-

cated in said receptacle and extending longitudinally of the longitudinal axis thereof, and a second similarly located and extending guide carried by said plug member and adapted to initially engage said first mentioned guide when the plug is inserted whereby said plug must be swung circumferentially to bring said movable contact elements into registry with said relatively fixed contact element when the plug is inserted.

5. In an electric conductor coupling, a relatively fixed cylindrically shaped wall receptacle provided within its interior with 15 insulated contact elements, a plug member of similar form in cross section, provided with spring resisted contact elements adapted to register with said first mentioned contact

elements at predetermined circumferential positions of said receptacle and plug members, a guide member eccentrically located in said receptacle and extending longitudinally of the longitudinal axis thereof, a similarly located and extending guide tube extending through said plug member and 25 adapted to pass over said first mentioned guide when the plug is inserted whereby said plug must be swung circumferentially to bring said movable contact elements into registry with said relatively fixed contact 30 elements when the plug is inserted, and means on said guide tube for locking said guide members in connected positions.

In testimony whereof I have affixed my signature.

THOMAS H. FENN.
